UNITED STATES PATENT OFFICE.

ARTUR NOLZEN, OF RONSDORF, GERMANY, ASSIGNOR TO THE FIRM: BERGISCHE ELEKTRIZITÄTS-GESELLSCHAFT GEBR. NOLZEN, OF RONSDORF, GERMANY.

FRESH-AIR HEATER FOR INTERNAL-COMBUSTION ENGINES.

Application filed March 6, 1926, Serial No. 92,795, and in Germany September 29, 1925.

The starting of internal-combustion engines, particularly in motor-cars, meets great difficulties in cold weather, because the fresh-air can initially be brought but difficulty 5 to the temperature required for producing the air and fuel mixture in the carbureter, said temperature being afterwards maintained by heating the carbureter by the exhaust. It has already been proposed to 10 heat the fresh-air to be sucked through the carbureter by the engine piston, temporarily, that is when starting the engine, by means of an electric heater arranged in front of the carbureter and to be operated by the electric 15 current used for lighting purposes in motor-cars.

The present invention relates to said known kind of heating the fresh-air, and it 20 consists in particular improvements therein 25 with the advantages hereinafter set forth with reference to the accompanying drawing, in which: Figs. 1 and 2 are respectively a front view and a side view of the improved heater arranged in front of the carbureter, while Fig. 3 is a horizontal section on the line A—B of Fig. 1; Fig. 4 being a modification of the heater adapted for use 30 behind the carbureter.

A casing 1 of short length is built in the 35 fresh-air conduit for the engine. With the heater arranged in front of the carbureter as shown in Figs. 1 to 3, the conduit and the carbureter are indicated by dotted lines in Fig. 3. The dimensions 40 of the casing 1 must, of course, suit the actual requirements. The electric heater consists (see Figs. 1 and 4) of a serpentine pipe 2, suitably of copper, of elongated round cross-section (Fig. 3) and arranged like a grate in and surrounded by said casing, and of an electric resistance 3 non-conductively mounted in said pipe. The ends 45 of the pipe 2 as well as its serpentine arcs

are cast in the body of the casing 1 made of an appropriate alloy. The ends of the resistance 3 lead, in the construction shown in Figs. 1 to 3, to the pole-pieces 4, 5 which are 45 screwed to terminals 6, 7 also cast in the body of the casing in insulating manner.

In the construction shown in Fig. 4 adapted 50 for use behind the carbureter, one pole-piece of the resistance 3 is conductively connected with the wall of the casing, that is cast therein, so that the terminal 6 with the pole-piece 4 is omitted. The casing 1 is then 55 conductively connected with the chassis of the motor-car, and only the terminal 7 with the pole-piece 5 is used for the lead to the battery.

The arrangement of a heater behind the 60 carbureter is advantageous because then even the smallest quantity of fuel mixture 65 that is required for starting the motor, is securely heated by being compelled to flow through the heater.

The pipe 2 serves thus by its free serpentine parts to heat the fresh-air flowing through the casing 1 and by its cast-in parts to also heat the casing itself.

What I claim, is:

In an internal-combustion engine, the combination of a casing of short length forming part of the fresh-air conduit for the engine, a serpentine pipe of elongated round cross-section arranged like a grate in and surrounded by said pipe, and an electric resistance non-conductively mounted in said pipe, the latter being cast at its ends as well as at its serpentine arcs in the body of said casing and thus capable of heating by its 75 free serpentine parts the fresh-air flowing through the casing and by its cast-in parts the casing itself.

In testimony whereof I have hereunto set my hand.

ARTUR NOLZEN.
